SPACE CONDITION RESPONSIVE INSTRUMENT

Henry Dreyfuss, South Pasadena, Calif., assignor to
Minneapolis-Honeywell Regulator Company, Minne-
apolis, Minn., a corporation of Delaware

Filed Oct. 24, 1962, Ser. No. 72,242

Term of patent 14 years

(Cl. D52—7)

FIGURE 1 is a front perspective view of the space condition responsive instrument embodying my new design;

FIGURE 2 is a front view; and

FIGURE 3 is a side view.

The essential features of my disclosed design reside in the portions shown in full lines.

I claim:

The ornamental design for a space condition responsive instrument, substantially as shown and described.
